CORD INSERTION DEVICE

George H. Leef, Minneapolis, Minn.

Application April 15, 1932. Serial No. 605,501

5 Claims. (Cl. 223—38)

My invention relates to devices for inserting strips of flexible material through tubular pockets and more particularly, to devices for inserting strips of elastic material through tubular pockets formed of flexible material.

Heretofore, strips of flexible or elastic material have been inserted in tubular pockets by means of rods or bokkins, such methods requiring considerable time and labor and often resulting in the strips becoming twisted when being inserted, or in the material forming the tubular pockets becoming soiled.

It is a specific object of my invention to provide a device for inserting elastic bands in the tubular pockets of steering wheel covers such as the cover described in my co-pending application Serial Number 572,285, filed October 13, 1931, but it will be understood that my invention is well suited for inserting cords or bands of elastic or flexible nature in the tubular pockets of many articles including tire covers, articles of clothing, cloth bags, and other articles.

An object of my invention is to provide a device of the class described whereby strips of flexible or elastic material can be quickly and conveniently inserted in tubular pockets.

Another object is to provide a device of the class described whereby strips can be inserted with a minimum amount of handling of both the strips and the material forming the tubular pockets.

Still another object is to provide a device of the class described for inserting strips whereby the possibility of the strips being twisted during insertion is eliminated.

A further object is to provide a device of the class described wherein the strips and the tubular pockets are held thereby in a suitable position to permit convenient joining of the two ends of each strip.

A still further object is to provide a device of the class described which is adaptable for simultaneous insertion of strips in any number of tubular pockets.

These and other objects and advantages of the present invention will more fully appear from the following description made in connection with the accompanying drawings, wherein like reference characters refer to the same or similar parts throughout the various views, and, in which,

Fig. 1 is a view of my steering wheel cover (described in my copending application Serial Number 572,285, filed October 31, 1931) as applied to the steering wheel of a motor vehicle;

Fig. 2 is a cross sectional view of a portion of my steering wheel cover taken along the line 2—2 of Fig. 1 as indicated by the arrows;

Fig. 3 is a side view of a portion of my steering wheel cover showing the openings in the tubular pocket thereof and partially broken away to show a section of the tubular pockets;

Fig. 4 is a side view of the ends of the elastic strip used in my steering wheel cover and the ring and spring snap used to join the ends of the strip;

Fig. 5 is a side view of my present invention with two elastic bands and a steering wheel cover in place thereon;

Fig. 6 is a top view of my present invention;

Fig. 7 is a vertical transverse section of my invention with two elastic bands and a steering wheel cover thereon taken along the line 7—7 of Fig. 5, as indicated by the arrows;

Fig. 8 is a vertical transverse section of my invention taken along the line 8—8 of Fig. 5, as indicated by the arrows;

Fig. 9 is a horizontal view of the end of one of the projecting arms of my invention with the spring snap on one end of a strip attached thereto, partially broken away to show the method of attachment;

Fig. 10 is a side view of the end of one of the projecting arms showing the spring snap on one end of a strip attached thereto;

Fig. 11 is a horizontal view of one of the projecting arms of my invention with the ring on one end of a strip attached thereto; and

Fig. 12 is a side view of one of the projecting arms of my invention with the ring on one end of a strip attached thereto.

Referring to the drawings, the steering wheel cover, in connection with which my invention is described, is formed of an endless strip 13 of cloth or other suitable flexible material, the edges 95 of which are folded inwardly and sewed or otherwise secured to the unfolded portion of the strip 13 to form tubular pockets 14. At diametrically opposite points the pockets are provided with openings 15. A strip 16, of elastic material such as rubber, on one end of which is secured a ring 17, and on the other end of which is secured a spring snap 18, is inserted through one of the openings 15 of each of the tubular pockets 14 and is threaded through said tubular pocket. The two ends of the strip 16 are connected by engaging the ring 17 with the spring snap 18. The cover is applied to a steering wheel 19 as shown in Fig. 1 and Fig. 2.

A rectangular base 20 is formed of plate steel 110

or other suitable material and is provided, adjacent each corner thereof, with an aperture through which a screw may be inserted for the purpose of attaching the base to a wall or other suitable surface.

A piece of small channel iron is formed into a pair of spaced parallel arms 21 of equal length connected together at their inner ends by a short transverse portion 21a of the channel iron, the 10 channel iron being so disposed that the flange of each arm extend toward the other arm of the pair. The transverse portion 21a is secured, in a horizontally disposed position, to the upper portion of the outer surface of the base 20 to support the arms 21 in horizontal, outwardly extending relation to the base. A second pair of arms 22, somewhat shorter than the arms 21 but otherwise identical thereto, are similarly supported by a transverse portion 22a attached to the lower 20 portion of the base 20 in a position parallel to and below the arms 21. One arm of each pair is rounded at the outer end thereof and formed to permit engagement therewith by a spring snap 15 as shown in Fig. 9 and Fig. 10. The remaining arm of each pair is formed at the outer end thereof into a blunt point which is adapted for being encircled by a ring 17 as shown in Fig. 11 and Fig. 12. The ring 17 has an internal diameter somewhat less than the width of the channel 30 iron from which the arms are made.

At the center point of each of the two transverse portions 21a and 22a, an outwardly projecting hook 23, formed from a metal rod, is secured. The rod forming the hook 23 associated with each 35 pair of arms is inclined slightly toward the opposite pair of arms and near its outer end is bent away from the opposite pair of arms so that the portion of the rod beyond the point at which it is bent is disposed vertically to form the hook 23.

40 Operation

The base of my device is normally rigidly attached to a wall or other suitable surface with the arms 21 and 22 extending horizontally outward from the wall.

The spring snap 18, secured to the end of an elastic strip 16, is engaged with the end of the corresponding one of the arms 21, the ring 17, secured to the other end of the same elastic strip, is looped over the end of the other arm 50 21, and the middle portion of the strip is engaged with the hook 23 associated with the arms 21 as shown in Figs. 9, 10, 11, 12 and 6. The 55 elastic strip is somewhat stretched and obviously is securely held in position. Another elastic strip is similarly placed in position on the arms 22 and the associated hook 23. The channel construction of the arms 21 and 22 permits the strips 16 to be received between the flanges of the channels to minimize friction and allow easy passage 60 of covers over the arms and the strips held by the arms. The arms 21 and 22 are plated or otherwise provided with a smooth surface to minimize friction.

65 A steering wheel cover, not yet containing elastic strips, is folded on a line through one of the pairs of associated openings 15. With the strips in place as previously described, the respective 70 portions of the tubular pocket communicating with one opening 16 are respectively slid onto the respective ones of the pair of arms 21 with the other opening 15 disposed therebelow and the respective remaining tubular portions of the pocket are similarly slid onto the arms 22 as shown in Fig. 7. The entire wheel cover is slid along the

80 arms 21 and 22 toward the base 20 to such a position that the ends of the arms 21 and 22 have emerged from the openings 15 opposite from the openings 15 referred to previously, as shown in Fig. 5. Then the ring 17 and the spring snap 18 85 engaged with the arms 21 are disengaged therefrom and the spring snap is engaged with the ring 18 to connect the two ends of the elastic strip together. The ends of the remaining elastic strip are similarly connected together. The complete steering wheel cover, with the elastic strips disposed within the tubular pockets thereof, is then drawn outward from engagement with the arms 21 and 22 and is ready for use.

90 Steering wheel covers of the type described are extensively used by garages, and the covers are laundered at frequent intervals. The elastic strips are removed preceding each laundering and the device of the invention may be used in quickly inserting the strips in place within the 95 covers after laundering.

95 It is apparent that I have invented a new and useful device for quickly and easily inserting flexible or elastic strips in tubular pockets with a minimum amount of handling of the strips and the 100 articles carrying the tubular pockets. It is also apparent that I have invented a device of the class described wherein the elastic strips are secured in position, after which the tubular pockets may be slipped over the strips, and where- 105 in the strips cannot become twisted during insertion thereof.

110 My invention, in the form described, is particularly adapted for use in inserting elastic strips in the steering wheel cover described in my co-pending application Serial Number 572,285, filed October 31, 1931, and has been described as so used. However, my invention is not limited in scope to this particular use but, obviously is well adapted for insertion of flexible or elastic strips in 115 tubular pockets of tire covers, articles of clothing, bags, and many other articles and may be arranged for simultaneously inserting any desired number of strips.

120 It will, of course, be understood that various changes may be made in the form, details, arrangement and proportions of the various parts without departing from the scope of the present invention.

125 What is claimed is:—

1. A device for inserting a flexible strip in a tubular pocket comprising a pair of spaced parallel arms, a transverse member connecting said arms at one end thereof, the free end of each arm being adapted to hold one end of a strip, and means adjacent said transverse member and rigidly mounted with respect thereto for engaging the middle portion of the strip.

130 2. A device for inserting flexible strips in tubular pockets, comprising a pair of spaced parallel arms, a transverse member connecting said arms at one end thereof, and a hook mounted on said member and extending between said arms toward the free ends thereof, the free end of each arm being adapted to hold one end of said strip and said hook being adapted to engage the middle portion of said strip.

135 3. A device for inserting flexible strips in tubular pockets comprising a base, two pairs of arms secured to and extending outwardly of said base, the end of each arm being adapted to hold the end of a strip, and means attached to said base between the arms of each pair for engaging the middle portion of a strip.

140 4. A device for inserting elastic strips in tubular
